(57) **CLAIM**

The ornamental design for the front face of a vehicle wheel, also known as Helo 833 as shown and described.

DESCRIPTION

FIG. 1 is a perspective view of a front face of a vehicle wheel showing my new design; and,

FIG. 2 is a front view thereof.

The broken line showing of environment is for illustrative purposes only and forms no part of the claimed design.

1 Claim, 2 Drawing Sheets

FIG. 1

FIG. 2
